United States Patent Office.

HIRAM BECKWITH, OF GRASS LAKE, MICHIGAN.

Letters Patent No. 63,693, dated April 9, 1867.

IMPROVED SCAFFOLD BRACKET.

The Schedule referred to in these Letters Patent and making part of the same.

TO ALL WHOM IT MAY CONCERN:

Be it known that I, HIRAM BECKWITH, of Grass Lake, in the county of Jackson, and State of Michigan, have invented a new and useful improvement in Roof Scaffold Bracket; and I do hereby declare that the following is a full, clear, and exact description thereof, which will enable those skilled in the art to make and use the same, reference being had to the accompanying drawings, forming part of this specification.

The object of this invention is to provide a safe, portable, and convenient, bracket for building scaffolds upon roofs where the roofs are covered or being covered with shingles; and the invention consists in the arrangement shown in the drawing.

Figure 1 represents the bracket complete, as when in use on the roof.

Figure 2 represents a portion of the same, it being the brace.

Similar letters of reference indicate corresponding parts.

A represents the shingle of the roof. B is an angular piece of metal, one portion of which forms a blade which rests on the shingle; the other portion, which stands at about right angles with the blade, is hinged at the top to another piece of metal of nearly the same form. C represents this second angular piece, the lower portion of which forms a blade like the first, and the other part standing also at right angles, or nearly so, with the blade. D is a brace, which is attached to this last-described piece C, and when the bracket stands upon the roof, as represented, the lower end of this brace D enters the shingle, forming a foothold, which prevents the bracket from slipping. A side view of this brace is seen in fig. 2. The blades are forced up under the shingle, as seen in the drawing; when the end of the brace D (which has teeth formed on it, as seen,) enters the shingle below and prevents the weight upon the scaffolding from raising the shingle, and the bracket from slipping. The arrangement and operation are so plainly shown in the drawing that no further description is necessary.

What I claim, and desire to secure by Letters Patent, is—

A roof bracket, constructed substantially as herein shown and described, with two blades with their back pieces, and supported by the brace D, for the purposes set forth.
